(57) **CLAIM**

The ornamental design for a laser transit, as shown and described.

DESCRIPTION

FIG. 1 is a front perspective view of the subject laser transit;
FIG. 2 is a rear perspective view of the laser transit as shown in FIG. 1;

FIG. 3 is a front view of the laser transit as shown in FIG. 1;

FIG. 4 is a rear view of the laser transit as shown in FIG. 1;
FIG. 5 is a left side view of the laser transit as shown in FIG. 1;

FIG. 6 is a right side view of the laser transit as shown in FIG. 1;

FIG. 7 is a plan view of the laser transit as shown in FIG. 1;
FIG. 8 is a bottom view of the laser transit as shown in FIG. 1;

FIG. 9 is a front perspective view of the laser transit as shown in FIG. 1 in which some parts are exchanged;

FIG. 10 is a front perspective view of the laser transit as shown in FIG. 1 in which some parts are exchanged;

FIG. 11 is a rear perspective view of the laser transit as shown in FIG. 10; and,

FIG. 12 is a right side view of the laser transit as shown in FIG. 1 in which some parts are exchanged.
